UNITED STATES PATENT OFFICE.

FREDERICK C. OVERBURY, OF HILLSDALE, NEW JERSEY.

ROOF AND METHOD OF LAYING.

Application filed July 14, 1923. Serial No. 651,477.

This invention relates to roofs and method of laying, and provides a construction whereby a copper or other suitable metallic surfaced roof may be produced by merely overlaying roofing units with the desired metal in thin sheet form, the metal being unattached to the base units over any considerable extent so that its expansion and contraction, due to heat changes, may 10 take place unhindered by the different rate of expansion and contraction of the underlying material whereby curling or warping of the roof material is prevented while retaining the strength and solidity derived 15 from the base units.

For a more complete understanding of this invention reference may be had to the accompanying drawings in which:

Figure 1 represents in perspective a piece 20 of base material herein shown as a strip shingle.

Figure 2 is a similiar view of the sheet metal strip for overlaying the strip shingles.

Figure 3 is a section on the line 3—3 of 25 Figure 2 showing the manner in which the lower edge of the metallic strip is bent.

Figure 4 is a fragmentary perspective of the finished roof.

Figure 5 is a section on line 5—5 of Figure 4.

By way of example this invention has been illustrated in connection with strip shingles such as are now commonly made by saturating rag felt with asphaltic or 35 bituminous material and surfacing them with grits such as crushed slate and cutting them into strips, each strip having along one edge shingle-simulating tabs formed by inwardly extending cut outs 3, it being common 40 in the art to form such strips in sections each containing four shingle-simulating tabs as illustrated in Figure 1. For the purposes of this invention a strip of copper, or other suitable metal in thin sheet form shown at 5 in Figure 2, is formed into general roofing element form with the cut out portions 6 mating the cut outs 3 in the strip shingle, but 45 preferably of greater depth so that when the metallic strip is superposed on the strip shingle as laid, as shown in Figures 4 and 5, the lower ends thereof extending beyond the ends of the shingle-simulating tabs. The 55 upper edge of the metallic strip may terminate short of the upper edge of the shingle strip, it being only necessary to cover the portions of the shingle strip ordinarily ex-

posed to the weather, but preferably the metallic strip extending sufficiently above the upper ends of the cut outs to form portions through which nails 7 may be driven to attach the metallic strips, and if desired the shingle strips also on the roof. The lower ends of the metallic strip tabs are then bent in under the ends of the tabs of the shingle strip as shown at 8.

The metallic strip may be in lengths similar to the shingle strips, or of different lengths, as may be desired, and they may be laid after each course of shingle strips have been laid and the lower ends then turned in 70 under the shingle-simulating tabs, or the two may be made fast to the roof together as may be found more convenient.

While as shown the base material over which the metal is laid is strip shingles, it is 75 evident that individual shingles could be treated in the same manner, as well as roll material, or any other form, it being only essential that the metal shall overlie the bases of the shingle material ordinarily exposed 80 to the weather, being preferably formed to engage beneath the lower edges of the base units in order to prevent detachment of the metal therefrom. It will be noted, however, that the strips are not attached to the base 85 material as by cement or otherwise so that they are free to expand and contract with heat changes entirely independently of the base material, to which they are held only by the nails for fastening the metallic strips 90 in position. A metallic surfaced roof is thus provided in which only very thin sheet metal is necessary since a substantial backing of roofing units of non-metallic material is provided.

Having thus described an embodiment of 95 this invention it should be evident to those skilled in the art that various changes may be made therein without departing from its spirit or scope as defined by the appended 100 claims.

I claim:

1. The method of laying a roof which comprises laying a course of non-metallic roofing elements, overlaying at least the portions of said elements exposed to the weather with thin sheet metal, turning the lower edge of the metal up under the exposed butt ends of said elements, fastening the metal in position, superposing in lapping 110 relation a course of non-metallic roofing units, and overlaying said course of non-

metallic roofing units in the same manner with thin sheet metal.

2. The method of laying a roof which comprises laying a course of non-metallic roofing elements, overlaying at least the portions of said elements exposed to the weather with thin sheet metal, turning the lower edge of the metal up under the exposed

edges of said elements, and fastening the metal in position by fastenings extending 10 therethrough above the portion which is normally exposed to the weather after the roof has been laid.

In testimony whereof I have affixed my signature.

FREDERICK C. OVERBURY.
